UNITED STATES PATENT OFFICE.

CHARLES HENRY DAVIS, OF RUSHWORTH, VICTORIA, AUSTRALIA.

POOL-BOARD.

1,205,596.

Specification of Letters Patent.

Patented Nov. 21, 1916.

Application filed January 8, 1916. Serial No. 71,057.

To all whom it may concern:

Be it known that I, CHARLES HENRY DAVIS, a subject of the King of Great Britain and Ireland, &c., residing at Rushworth, 5 in the State of Victoria, Commonwealth of Australia, have invented certain new and useful Improvements in Pool-Boards; and I do hereby declare the following to be a full, clear, and exact description of the invention, 10 such as will enable others skilled in the art to which it appertains to make and use the same.

This invention relates to an improved score board or apparatus for pool and other 15 games, and is of that kind by which the exchange, loss, or mislaying of the marbles, and the exposure of them to persons who should not know the numbers thereon are avoided. In this specification the word 20 "marble" will equally mean any ball or indicator appropriate to the game to be played. Any player can examine his marble at any time, but will not retain it in his possession.

At the game end any player can look at a 25 winner's marble, so that confidence in the result will be promoted. In using such an apparatus it is desirable that time shall be saved, so that the convenience of the players shall be promoted, and the earning power of 30 the establishment having the pool board increased; and with that in view I provide special arrangements for gathering the marbles at the end of a game into a bottle. I provide also a special device for holding 35 marbles which, during a game, are set out of use. On all pool boards there is a surface to receive the score.

In the accompanying drawings, Figure 1 is a perspective view of my apparatus with 40 its score receiving board removed, the marble receiving bottle being shown. Fig. 2 is a front elevation showing the apparatus with the score receiving board or front plate in use. At the top of the apparatus there is shown 45 in vertical section, a movable bar containing pockets into which marbles will be placed. At the left of this figure the said bar is in normal playing position, but at the right it is in the temporary position in which it 50 will be pushed when a game is ended. Fig. 3 is a vertical section of some details, and Fig. 4 shows, on a larger scale, a horizontal section of other details. Various parts of 55 Figs. 1 to 3 are omitted to allow these figures to be included on one sheet of regulation size. Fig. 3 is modified from Figs. 1 and 2.

In these drawings, *a* indicates a score receiving plate or board of any suitable shape, size and material, as wood or slate, divided into columns *b*, adapted to be headed 60 by a person in attendance—as a billiard marker—from time to time to distinguish the different players by initials, names, numbers, or so on. Thus, in a headline *c*, the names "Tom," "Bob," and "Alf" in Fig. 2 65 indicate several players by way of example. As example of pool scores,—which will ordinarily in practice be chalked on,—is shown, in which, provided the marble of "Tom" is numbered "16," he is a winner. "Alf" is 70 marked as having failed to score. The numbers with which the marbles will be marked appear on the board at *d*.

The apparatus can be attached where required as by means of eye plates *q*⁴ on its 75 frame, and possesses—besides a head, sides *q*¹, a base *q*², and a back *q*³,—the said front board *a* being either fixed in place or movable to expose the interior. The whole thus forms a hollow box which is narrow from 80 front to rear, and the interior of which I use.

The apparatus head includes a fixed member *n* having a frontal lip, and extending over the board *a* horizontally. Above member *n* is a slidable bar *g*, adapted to act as a marble receiver and releaser. This bar has a series of open topped pockets *h*, each for one marble, and sufficient in number to allow 85 of the maximum number of players for 90 which the board is designed. Each player on receiving his marble must take notice of and should remember the number on it, so as to know when his score reaches the winning total 31. The attendant or marker also 95 notes the number and then the said marble is dropped into the correct pocket of bar *g*, that is the pocket immediately over the player's score column *b*. Thus the marble *x* in Fig. 2 is "Bob's." The other marbles 100 used in practice are omitted from the drawing. If a player desires his marble shown him during the game, then the attendant must return it to the pocket from which he removed it to show him accordingly. 105

Each pocket *h* has a frontal outlet *g*¹ which is normally kept closed by a movable member or gate *u*, which may be pivoted to the bar *g* by a pin *u*¹; after being raised, and as soon as released it will drop back 110 again, in my preferred construction. Each pocket bottom *h* is integral with or fixed to

the member carrying the lip n , and normally these bottoms support the series of marbles in the series of pockets. Between successive bottoms k are apertures or spaces 5 m , so that when the bar g has been moved longitudinally to its releasing position (at the right in Fig. 2) each pocket h is bottomless, being over an aperture m . Thus the marbles in all the pockets drop into the 10 interior of the apparatus.

The dropped marbles are received upon a conducting surface formed by an inclined partition j (shown with a groove j^1 , which is quite optional and a minor detail) on 15 which they roll or slide to a passage or funnel o , which is over the mouth of a receiving bottle p . The ends of the bar g are marked i .

To insure the correct placing of the bottle 20 there is a gap or recess p^1 , of appropriate shape, provided alongside a lower corner part of the board a , which is shown cut to have an edge f^1 , to allow of the bottle being 25 insertible only in the right position for receiving the marbles. The bottle is at will removed by hand. The base of the recess is the bottle support. The funnel or passage o , and the recess p^1 can be formed by fixing inside the apparatus partitions or 30 studs o^1 and f between the front board a and the back one q^2 . To allow of, and yet to limit to what suits the pockets, the sliding movement of the bar g , it has means as slots s , through which extend from the ledge 35 n posts s^1 ; and to prevent movement of the bar g while a game is in progress there is a keeper. As shown in Figs. 1 and 4 the keeper t is slotted at t^1 , and is housed in a hole g^2 in the bar g , and its complete with- 40 drawal is prevented by a pin w which is inserted in the bar g , and except at its ends, is within the slot t^1 . By withdrawing the keeper sufficiently, in the direction of the arrow, it leaves the bar g slideable as de- 45 scribed. Upon the transverse lip n is a series of inclined channels k^1 , leading from the respective pocket outlets g^1 . When, by raising a gate, a marble which rested against the gate interior is caused to leave its pocket 50 h , that marble will fall into any hand which may be held at the outer end of the channel used.

In playing pool it often happens that 55 several marbles have to be set aside and that there is not a convenient place for them. But I provide one or more inlet apertures r in the framing, so that the surplus marbles can be inserted into one or more receiving chambers between the front and back 60 plates of the apparatus.

r^1 is a sloping base of a chamber, formed as by providing a member r^2 . The chamber has an exit r^4 , closed normally by any suitable means as a plate r^3 . I have ordinarily 65 sufficient chambers (of small size as at r^5 in

Fig. 3) to allow of one marble in each; then the marker or attendant can withdraw at once the marble which bears a particular number, and thus better suit the conditions appertaining to the entry of another player 70 into the game. Although only a few inlets r for marbles are shown, it will be understood I may use 8 or even more. In Fig. 3 r^6 is a pivoted or movable member, to serve as the base of a marble chamber, and having a projection r^7 by depressing or moving which the marble can be caused to roll or drop out of hole r into the marker's hand. Instead of a tilttable base, a slidtable one to draw out could be used, or any other suitable 80 form of recess made. It is made easy to move the plate r^3 , as by swinging it to one side, to recover whatever marbles have been introduced at r . In my claims the word bottle is intended to include any suitable 85 vessel.

Having described this invention, what is claimed by Letters Patent is:—

1. In an apparatus of the character described, the combination with a box or casing having a head provided with a plurality of openings, of a slideable bar arranged over said head and provided with a plurality of ball-receiving pockets adapted to coincide with the openings in the head when the said bar is operated as described, a ball conductor arranged within the casing and adapted to receive the balls falling through the openings in the head, and means arranged within the casing to form a funnel into which the balls are conducted by the said conductor and a receptacle arranged to receive the balls passing downwardly through the funnel.

2. In an apparatus of the character described, the combination with a box or casing having a head provided with a plurality of openings, of a slideable bar arranged over said head and provided with a plurality of ball-receiving pockets adapted to coincide 95 with the openings in the head when the said bar is operated as described, each of said pockets being open at the top and having a frontal outlet, a pivotal gate adapted to close the frontal outlet of each pocket, a ball conductor arranged within the casing and adapted to receive the balls falling 100 through the openings in the head, and means arranged within the casing to form a funnel into which the balls are conducted by the 105 said conductor, and a receptacle arranged to receive the balls passing downwardly through the funnel.

3. In an apparatus of the character described, the combination with a box or casing having a head provided with a plurality of openings, of a slideable bar arranged over said head and provided with a plurality of ball-receiving pockets adapted to coincide 125 with the openings in the head when the said 130

bar is operated as described, means for limiting the sliding movement of the slidable bar, means for locking the said bar against movement, a ball conductor arranged within the 5 casing and adapted to receive the balls falling through the openings in the head, means arranged within the casing to form a funnel into which the balls are conducted by the said conductor, and a receptacle arranged to 10 receive the balls passing downwardly through the funnel.

4. In an apparatus of the character described, the combination with a box or casing having a head provided with a plurality 15 of openings, of a slidable bar arranged over said head and provided with a plurality of ball-receiving pockets adapted to coincide with the openings in the head when the said bar is operated as described, means for limiting the sliding movement of said bar comprising a post on the head projecting within a slot in the slidable bar, means for locking the bar immovable when desired comprising a keeper provided with a slot and movably 20 arranged within a recess in the bar, said keeper being adapted to occupy a position transversely of the slot in the bar adjacent the aforesaid post, a ball conductor arranged within the casing and adapted to receive the 25 balls falling through the openings in the head, means arranged within the casing to form a funnel into which the balls are conducted by the said conductor, and a receptacle arranged to receive the balls passing 30 downwardly through the funnel.

5. In an apparatus of the character described, the combination with a box or casing having a head provided with a plurality of openings, of a slidable bar provided with 35 a plurality of ball-receiving pockets adapted to coincide with the openings in the head when the said bar is operated as described, an inclined conducting surface arranged in the casing to receive the balls falling through 40 the openings in the head, partitions arranged within the casing to form a passage for the balls falling from the said inclined conducting surface and also to form a recess, and a

ball-receiving receptacle arranged in said recess to receive the balls falling downwardly 50 through the said passage.

6. In an apparatus of the character described, the combination with a box or casing having a head provided with a plurality of openings and a lip having a plurality of inclined channels, of a slidable bar arranged over said head and provided with a plurality of ball-receiving pockets adapted to coincide with the openings in the head when the said bar is operated as described, and said 60 pockets having frontal outlets adapted to conduct balls onto the aforesaid inclined channels, a ball conductor arranged within the casing and adapted to receive the balls falling through the openings in the head, 65 means arranged within the casing to form a funnel into which the balls are conducted by the said conductor, and a receptacle arranged to receive the balls passing downwardly through the funnel. 70

7. In an apparatus of the character described, the combination with a box or casing having a head provided with a plurality of openings, and one of the side walls of the casing being provided with a series of 75 apertures, and a pivotal ball-receiving member arranged within each of said apertures and adapted to be tilted to discharge a ball through an aperture exteriorly of the casing, of a slidable bar arranged over said 80 head and provided with a plurality of ball-receiving pockets adapted to coincide with the openings in the head when said bar is operated as described, a ball conductor arranged within the casing and adapted to 85 receive the balls falling through the openings in the head, means arranged within the casing to form a funnel into which the balls are conducted by the said conductor, and a receptacle arranged to receive the 90 balls passing downwardly through the funnel.

In witness whereof I have hereunto set my hand.

CHARLES HENRY DAVIS.
